APPARATUS FOR TESTING FLAME
SAFETY LAMPSEugene E. Quenon, Pittsburgh, Pa., assignor to
the Government of the United States, as repre-
sented by the Secretary of the Interior

Application February 27, 1943, Serial No. 477,485

3 Claims. (Cl. 73—164)

(Granted under the act of March 3, 1883, as
amended April 30, 1928; 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467).

This cabinet is designed for simultaneously testing a plurality of flame safety lamps in explosive mixtures of air and gas. This cabinet permits close scrutiny of the action within each lamp while the igniters of the lamp are struck successively. A dangerous defect in any of the plurality of lamps being tested will cause a visible and audible explosion within the cabinet, rupturing a paper diaphragm, and unmistakably indicating that the lamp just ignited is defective. At the conclusion of a test of a plurality of lamps the design permits voluntary ignition and explosion of the mixture of air and gas within the cabinet, proving that the existing mixture is explosive and that none of the lamps in the cabinet will transmit an internal ignition to an external explosive mixture. This test of one or more flame safety lamps is made in a still air-gas mixture such as may be encountered in mines or other underground workings, and promptly detects any dangerous undetected defect, so that each working shift knows that all lamps are safe when they start into a mine.

A preferred form of my invention is disclosed in the accompanying drawings in which—

Figure 1 is an elevation of my device partly in section.

Figure 2 is a section on the line 2—2 of Figure 1.

Figure 3 is a section on the line 3—3 of Figure 2.

Figure 4 is a detail on the line 4—4 of Figure 2.

In these drawings, 11 is a cabinet provided with a sufficiently gas-tight closure 12 which, for convenience, is hinged at the bottom, and held in closed position by a plurality of trunk clamps or the like. My cabinet is divided into an upper chamber 9, and a lower chamber 10 by a partition 13 provided with a plurality of apertures 14 and divided into two sections along the center line of said apertures, one partition section being attached to the stationary portion of said cabinet and the companion section being secured to the closure so that when the cabinet is fully open a plurality of flame safety lamps 15 may be laterally entered in the said apertures 14 as well as in aligning recesses 16 which are formed in the bottom of my cabinet. Each recess connects with

a smaller concentric aperture 17 to permit the operation of the lamp igniter while the lamp is in the cabinet. Opposite each lamp there is a small circular window 18, permanently closed by any suitable transparent material, such as scatter-proof glass, for watching the action of each lamp while undergoing a test. For steadyng the lamps against accidental movement while my cabinet is open, I provide a plurality of resilient clamps 19, each detachably supporting the upper portion of a lamp. The upper chamber of my cabinet is provided with a plurality of openings 25 to permit the expulsion and replacement of the contained air by the incoming mixture of air and gas. These openings are not stoppered or otherwise closed. A plurality of openings in ends of the lower chamber are fitted with frictionally held stoppers 26 to relieve the force of explosions in the lower chamber.

In order that an explosion of the mixture within my cabinet may be rendered harmless as well as to provide a visual means for recording an explosion, I provide a shouldered aperture 20 which is normally closed by a sheet of paper 21 detachably held in position by a clamping frame 22.

A suitable inflammable gas, preferably "natural" gas from utility mains or a pressure bottle is supplied through a supply pipe 23 to one or more mixing devices 24 of the Bunsen-burner type to form an air-gas mixture, preferably about ten percent gas which has been found to be the percentage of gas which would have the maximum rate of flame propagation when ignited, and therefore provides the most severe test for a flame safety lamp. The pressure of the inflowing gas is measured by a U-shaped water gauge 29, and regulated by the gas cock 30. The admission of the gas at a predetermined pressure measured by the water gauge, will properly proportion the air-gas mixture desired in the cabinet.

Beneath each of the apertures through the partition 13 are split rings of soft incombustible packing material 27 to seal the upper from the lower chambers and thereby compel the air-gas mixtures to pass through the lamps instead of around them. When it is desired to test a lesser number of flame safety lamps than the cabinet is designed to contain, the openings not occupied by lamps may be closed in any convenient manner.

An igniter 28 of the common "flint" or pyro-
genic alloy type used in flame safety lamps, pro-
vided with an external operating handle 32 per-
mits the voluntary ignition of the mixture within
the upper part of the cabinet.

The procedure in testing a plurality of flame

safety lamps by means of my apparatus is to first place an unlighted lamp in each of the lamp holding devices, see that the stoppers 26 loosely fit in each end of the cabinet and that a paper diaphragm is in position on the top, close and fasten the cabinet, open the gas cock until the water gage registers the predetermined pressure and, after an interval determined by trial, turn off the gas.

After the gas and air have been thoroughly mixed, this test gas flows into the lower chamber of my cabinet around the fonts of the lamps being tested, and being lighter than air, as well as being injected at a slight pressure, it flows into and through the flame safety lamps, thence through the inner and outer gauzes into the upper part of my cabinet. This directed flow carries off the concentrated vapors of the fuel from freshly filled safety lamps, expelling the fuel vapors and the contained air from the cabinet, and establishes a substantially homogeneous mixture of about 10 per cent gas and air within the lamps and cabinet.

A gas flow of 3 minutes' duration at a water gage pressure of about 10 inches was found to be sufficient in apparatus actually used. Then by means of the individual lamp igniters 31, light each lamp in quick succession, noting the explosions within each lamp as seen through the small windows, and finally to determine whether or not the explosive mixture was properly proportioned, ignite the mixture surrounding the lamp by means of the handle 32 of the igniter 28. This last test also serves to consume the explosive mixture which would otherwise be released when the cabinet is opened.

This cabinet is inexpensive to construct, more closely simulates actual conditions in a mine than same earlier types, operates with certainty, and can be understood and operated by anyone familiar with flame safety lamps.

The form which has been illustrated and described may obviously be modified and therefore is not intended to restrict any claims of this application.

What I claim is:

1. Apparatus for testing flame safety lamps which comprises an apertured partition detachably positioned to engage the central portion of at least one such safety lamp, means for confining an explosive gaseous medium on one side of said partition to surround one projecting portion of each lamp, means for confining a similar ex-

plosive gaseous medium on the opposite side of said partition to surround the oppositely projecting portion of each lamp, means for introducing an explosive gaseous medium into one of

5 said gas-confining means, a vent on the other gas-confining means for permitting escape of displaced air, means for releasing excess pressure from each of said gas-confining means, remotely-controlled means for igniting each lamp, and

10 10 remotely-controlled means for igniting explosive gas confined on at least one side of said partition.

2. Apparatus for testing flame safety lamps which comprises an apertured partition detachably positioned to engage the central portion of at least one such safety lamp, means for confining an explosive gaseous medium about the upper portion of each lamp, means for confining a similar explosive gaseous medium about the lower

20 portion of each lamp, means for introducing an explosive gaseous medium into one of said gas-confining means, means for permitting escape of displaced air from the other gas-confining means, means for releasing excess pressure from each of

25 said gas-confining means, remotely-controlled means for igniting each lamp, and remotely-controlled means for igniting explosive gas confined about the upper portion of each lamp.

3. Apparatus for testing flame safety lamps

30 which comprises a gas-confining cabinet having at least one detachable side, an apertured partition positioned horizontally therein and vertically divided into at least two parts through each aperture, one part of said partition being attached to said cabinet and another part being attached to the detachable side of said cabinet whereby said partition defines an upper gas-confining chamber and a lower gas-confining chamber, resilient sealing means in each aperture adapted to engage each lamp positioned therein

35 40 whereby gas in one chamber can migrate to the other only by passing into and through a lamp, means for introducing an explosive gas mixture into the lower gas-confining chamber, means for purging displaced gases from the upper chamber, means for indicating explosions and relieving excess pressures, igniting means provided with externally operated mechanism for separately lighting each lamp, and igniting means

45 50 provided with externally operated mechanism for igniting gas in said upper chamber.

EUGENE E. QUENON.
